CLAIM

The ornamental design for a billiard cue bag, as shown and described.

DESCRIPTION

FIG. 1 is a front perspective view of a billiard cue bag showing our new design;

FIG. 2 is a bottom perspective view of the billiard cue bag showing our new design;

FIG. 3 is a right side elevation view of the billiard cue bag showing our new design;

FIG. 4 is a left side elevation view of the billiard cue bag showing our new design;

FIG. 5 is a front view of the billiard cue bag showing our new design;

FIG. 6 is a rear view of the billiard cue bag showing our new design;

FIG. 7 is a top view of the billiard cue bag showing our new design;

FIG. 8 is bottom view of the billiard cue bag showing our new design; and,

FIG. 9 is a perspective view of the billiard cue bag in an open position showing our new design.

The parallel oblique broken lines indicating stitching, that appear on the right and left sides of the billiard cue bag in FIGS. 1-4 and 9, form part of the claimed design. The remaining broken lines shown in all figures—defining pockets, zippers, holes, and other features—are for illustrative purposes only and form no part of the claimed design.
